(57) **CLAIM**

The ornamental design for a rack for cup holder, as shown and described.

DESCRIPTION

FIG. 1 is a perspective view of a rack for cup holder, showing my new design;

FIG. 2 is a front view thereof;

FIG. 3 is a bottom view thereof;

FIG. 4 is a top view thereof;

FIG. 5 is a rear side view thereof;

FIG. 6 is a left side view thereof;

FIG. 7 is a right side view thereof; and,

FIG. 8 is a perspective view of rack for cup holder for holding cup on a desk.

The broken line portion of the figure drawings is included to show portions of the article that forms no part of the claimed design.
